METHOD AND APPARATUS FOR THE PRODUCTION OF FILAMENTS FROM SOLIDS

Filed Sept. 29, 1943

UNITED STATES PATENT OFFICE

2,437,263

METHOD AND APPARATUS FOR THE PRODUCTION OF FILAMENTS FROM SOLIDS

Fred W. Manning, Palo Alto, Calif.

Application September 29, 1943, Serial No. 504,525

11 Claims. (Cl. 18-8)

1 My invention relates to devices for the dispersion of fusible solids into the filaments to form fabric coverings, and droplets to form film coatings, and particularly relates to guns for such purposes. This application is a continuation-in-part of my copending applications, "Method and apparatus for spinning unwoven fabrics," Serial No. 414,809, filed October 13, 1941, and "Method and apparatus for making unwoven and composite fabrics," Serial No. 423,733, filed December 20, 1941, subsequently issued as Patents Nos. 2,336,743, and 2,336,745, respectively.

Prior practice has been to limit the use of spray guns to the disruption of substances into droplets, which were projected against surfaces where they flattened out into overlapping scales and then became indurated into hardened coverings. Some of these materials, such as certain metals, were instantly sprayed from a solid state into droplets without there being any apparent intermediate period or position in which the metal could be recognized as existing in a fluid state. As far as I am aware, no attempt has ever been made to use a spray gun to bring a solid to a fluid state before its disruption into droplets, or to attenuate such a fluid into a plurality of filaments and disperse and deposit the filaments to form a non-woven fabric.

It is therefore the primary object of my invention to provide an inexpensive method and means for bringing a solid to a fluid state, disrupting it into a plurality of filaments, and projecting the filaments in an adhesive state upon the object to be coated or covered by intersecting filaments. Such a non-woven fabric can then be sprayed by droplets to form a film; thereafter, which coating may cover the filaments alone to protect the latter and leave the fabric pervious, or the film may also cover the interstices and leave the fabric impervious, or the film covering for filaments and/or interstices may leave the fabric pervious to certain fluids and impervious to other fluids. These composite fabrics may then be sprayed or otherwise coated by treating fluids or solids in finely divided form, such as the usual fire retardants, water repellents, wetting agents, lacquers, adhesives, solvents, non-binder fibres, etc.

In accordance with my invention, I propose to use spinning materials which are usually thermoplastic but may be thermosetting. A great variety of plastics may be used for as many different purposes, such as: vinylidene chloride, vinyl chloride acetate, polyvinyl chloride, polyvinyl butyral, polystrene, polysulphide, polyvinyl alcohol, poly-

5 vinyl acetate, methyl methacrylate, and polymeric amide resins, urea-formaldehyde and phenol-formaldehyde compounds, latex compositions, cellulosic and petroleum derivatives, protein-base materials, glass, mixtures of organic and inorganic materials, such as the plastics now called "silicones," and almost all materials that are now spun or extruded into filaments, films, and foils. These materials may be modified by other materials, such as plasticizers, coloring agents, volatile solvents, etc., but which are most suitable for any particular purpose will depend upon the temperatures involved, corroding effects of contacting fluids, cost of the plastics, and many other factors. Such plastics may be fed in powder, granular, rod, or other solid form, into a reduction zone, the solid subjected to heat and/or pressure to reduce it to a fluid state, the fluid plastic attenuated or disrupted into filaments, or other discrete particles, at a given speed by a pressure differential, and the said particles stretched or/and dispersed and deposited by propelling movements of adjacent or enveloping elastic and/or liquid fluids moving at a greater speed than the extrusion speed.

2 All plastics that can be spun directly into such filamentous structures can also be sprayed in droplets to make film coatings for the structures, but many materials that can be sprayed in droplets cannot be spun into filaments. There are many ways of making a non-woven fabric of intersected filaments impervious to fluids and fluids containing moisture, etc. If the fabric is to be made homogeneous the individual filaments 30 may be caused to flatten out and assume an oval shape by projecting them against a retaining wall with considerable impact, and ultimately an impervious fabric of promiscuously intersected filaments will result; or both filaments and droplets of the same material may be deposited in a plastic state by the same fluid stream and from the same gun, the filaments being extruded from an integral mass in a reduction chamber into the fluid stream where they may be further extended, 35 disrupted and dispersed, and the droplets resulting from the introduction of the plastic in finely divided solids from another source of supply into the same stream and reduced therein to droplets by the heat of the stream; or the droplets may 40 be sprayed subsequently to the filaments and from the same reduction zone by varying the disruption viscosity of the plastic, pressure and direction of the air blast, etc. If the fabric does not require to be homogeneous, a composite 45 structure may be spun from a variety of plastics,

the spinning being accomplished simultaneously by using a different gun for each plastic, or different plastics may be spun successively from the same gun; or a composite structure may be built up of materials that can be spun into filaments, such as those already mentioned, and fusible solids that can only be sprayed in droplets, such as certain metals and enamels. Any homogeneous or composite structure of fusible materials may also be sprayed or otherwise coated with fusible synthetic fibres, such as nylon, rayon, glass, etc., or with non-fusible natural fibres, such as cotton, wool, hair, feathers, asbestos, shredded leather, etc., to increase the warmth of the fabric, improve its appearance, strengthen its structure, etc. When non-binder natural fibres are bonded by thermoplastic or thermosetting fibres in an adhesive state, the latter may vary by weight from 5 to 25 per cent or over of the former, and as indicated above, the binder and non-binder fibres may be commingled during conveyance and be deposited in mixed condition, or they may be conveyed separately and deposited in alternate layers, and their adherence and the induration of the binder fibres may be accomplished during conveyance or after deposition.

A plurality of elastic or liquid fluid blasts or streams may be used in the gun for coating and covering objects with filaments and droplets. A primary elastic or liquid fluid, controlled and directed by a primary nozzle, may be positioned adjacent to, or envelope, the extrusion orifice and flow therefrom for the purposes of: creating the necessary differential pressure required to extrude a filament; cooperating with a positive or other means within the gun for the same purpose; stretching, conveying, dispersing, and depositing the extruded filaments; maintaining the extrusion block and extruded filaments at a suitable temperature so that the latter may be conveyed and deposited in a plastic state; disrupting continuous filaments, as they are extruded, into broken lengths; and conveying, reducing, and dispersing a liquid or finely divided solids, for coating purposes, bonding indurated filaments together, bonding indurated filaments by droplets, etc. A secondary elastic or liquid fluid, enclosed and directed by a secondary nozzle, may be positioned adjacent to, or envelope, the primary fluid and flow at a greater velocity than the latter for the purposes of: controlling and directing the primary fluid flow to regulate the deposition of filaments and/or droplets, and to prevent the plastic filaments from contacting the nozzle barrel; increasing the velocity or impacting force of filaments as deposited; regulating the oxidizing action of the primary fluid; and for quenching or/and shrinking the filaments during their conveying and stretching period, or after their deposition.

There may be used for the above mentioned purposes: fluids that will sustain combustion, such as oxygen and such as steam and carbon dioxide; non-oxidizing fluids, acetylene; products of combustion, such as helium, nitrogen, hydrogen, argon, and carbon dioxide; and in some cases liquid fluids may be substituted for elastic fluids, such as a cold water spray or stream for quenching and shrinking the filaments or the newly-formed fabric. For most purposes, however, both primary and secondary fluids should be inert in their relation to the plastic filaments and droplets, the former fluid being maintained at substantially the same temperature as, or only slightly lower than, the molten

or extrusion temperature, which will usually vary between 250° F. and 500° F. for organic thermoplastics but may reach as high as 2200° F. for inorganic thermoplastics, the latter fluid being maintained at a lower temperature for rapid quenching and indurating purposes, which will usually vary between 50° F. and 60° F. but may be anything above freezing point; and the primary fluid may or may not be immiscible in the secondary fluid. And either or both primary and secondary fluids may be given a whirling motion by means of helicoid vanes or tangential openings within the primary and/or secondary nozzles to aid in stretching the filaments during their conveyance, or to twist a plurality of filaments about one another to form a yarn or a stronger fabric structure.

The strength of the deposited filaments and the structure formed by the union of the intersecting filaments will depend on many factors, such as the plastic used, the amount of stretching given to the extruded filaments, the temperature at which the filaments are stretched, etc.; and the stretching may be increased by increasing the propelling speed of the conveying fluids over the extrusion speed of the filaments, and also by controlling the direction of their propulsion before any substantial dispersion is allowed to take place, as by use of a nozzle of substantial length. If the stretching of the filaments is to be accomplished wholly by the heating or primary conveying fluid the primary nozzle may be short, or it may be from one to six feet or more in length, in which case the secondary nozzle and quenching fluid will usually not be required; if the filaments are to be cold drawn the secondary nozzle should be of substantial length, as from one to six feet or more in length. However, for most purposes both primary and secondary fluids will be used for stretching purposes, and the length of each nozzle will have a definite relative relation to the amount of stretch required from the movement of the fluid directed by its respective nozzle, and the length of the nozzles and the flare of their outlets will determine the dispersion of the deposited filaments. The length of the filaments at deposition will depend on the extent they are subjected to opposing forces during conveyance and stretching, kind of plastic, etc. They may be stretched and deposited in continuous lengths and in a uniformly intersected condition, with or without aid from the conveying fluids, by reciprocating, rotative, or other regular movements of either, or both, gun and object being coated; or they may be deposited in broken lengths in a promiscuously intersected condition, in which case the actual lengths of the filaments in an integral fabric will seldom be apparent.

The invention is exemplified in the following description, and a preferred arrangement is illustrated by way of example in the accompanying drawings, in which:

Figure 1 is a vertical section of a gun for spinning and spraying purposes.

Figure 2 is a cross-section taken on line 2-2 of the propulsion cylinder shown on Figure 1.

Figure 3 is a fragmentary section taken on line 3-3 between the primary and secondary nozzles shown in Fig. 1.

The gun consists of three major parts: a fluid motor for feeding a solid rod 1 of filament or droplet forming substance into a gun barrel, the barrel in which the rod is reduced to a fluid state

and then disrupted into filaments or droplets, and a gun stock to which both are attached.

The motor has complementary forward and rear cylinders 2 and 3, respectively, separated by a division plate 4 and closed by forward and rear threaded cylinder heads 5 and 6, respectively, the latter having a hole therethrough which is reduced to a diameter slightly less than that of the rod to act as a sealing ring therefor. The forward and rear pistons 7 and 8, respectively, are similar in construction, and each encloses a plurality of gripping balls 9, ball ring 10, spring 11, closure plate 12 for the spring, snap ring 13 for the closure plate, sealing ring 14 for the rod, and a snap ring 15 for the sealing ring. A reduced portion 16 of the pistons traps air in recessed portions 17 of the division plate and the rear cylinder head to cushion the rapid rearward movement of the pistons. The valve chamber 18 is closed by forward and rear plugs 19 and 20, respectively, and encloses a piston valve having division heads 21, 22, 23 and 24, through the first and last of which are small exhaust passages 25 and 26, respectively. Air pressure enters the valve chamber at port 27, and the exhaust escapes from the chamber through ports 28 and 29. A passage 30 runs the length of the cylinders and is connected thereto by forward and rear ports 31 and 32, respectively, and to the valve chamber by port 33. The cylinders are connected by passage 34, and to the valve chamber by ports 35, 36 and 37.

The gun barrel 38 encloses: concentric mica insulating tubes 39 and 40 for enclosing the heating element 41, concentric mica insulating tubes 42 and 43 for enclosing the heating element 44, a concentric air heating chamber 45 between the two heating elements, and a guiding tube 46 connected to the forward cylinder head for the plastic rod. An extrusion head 47 is attached to the end of guiding tube and has a plurality of openings 48 to aid in disrupting the molten plastic into filaments, and a plurality of openings 49 connected to the concentric air heating chamber. A primary nozzle 50 having an outlet 51, and a secondary nozzle 52 having an outlet 53, are adjustable within the end of the gun barrel, and the annular chamber between the two nozzles is connected by tangential openings 54 through the barrel with the annular space 55 within the ring 56.

The gun stock 57 has therein a main air passage 58 opened by means of the trigger 59, which is supported by a pin 60, making pressural contact with the valve 61, the latter being held in normal position by a spring 62 within the cap 63. Leading from the underside of the valve is an air passage 64, which is divided into a number of branches; an air passage 65 to the piston valve chamber, which is controlled by an adjusting screw 66 within a packing nut 67; an air passage 68 to the pipe 69, which communicates with the opening in the annular gun ring and is controlled by an adjusting screw 70 within a packing nut 71; and an air passage 72 to an annular opening 73, which communicates with the concentric air heating chamber and is controlled by an adjusting screw 74 within a packing nut 75. A passage 76 also runs through the gun stock for the electric wires 77, which are connected through passages 78 and 79 with the thermostat 80 and the heating elements. The gun barrel is attached to the stock by a screw thread, and the motor cylinders are held in a recess portion of the stock by bolts 81. An injector 82 and 75 and the entire heating and disruption of the rod

cock 83 control admission of fluids or solids into the quenching or secondary fluid, and opening 84, which is shown closed by plug 85, may be used for feeding fluids or solids into the heating or primary fluid, the movement of the secondary and primary fluids through their respective passages being sufficient for such injection purposes.

The operation of the gun thus constructed has been indicated in connection with the foregoing description with the exception of the movements of the feeding cylinders and piston valve. The rearward movement of the pistons cause the gripping balls 9 within the pistons to move slightly forward relatively against spring pressure so as to offer no resistance to the movement of the pistons, but their forward movements cause the balls to jamb between the internal conical structure of the pistons and the rod thereby gripping the latter and causing it to travel with the pistons. In the position of pistons as shown, air pressure flows from the supply branch 65, through ports 27 and 33 of the valve chamber into the longitudinal passage 30 and from the latter through end ports 31 and 32 into the extreme ends of the forward and rear cylinders, respectively. The forward piston 7, being under no load, flies back instantly to division plate 4; the rear piston moves forward as quickly as the forward end of the rod is reduced to a fluid state by the heating elements and the molten plastic forced through the extruding openings 48 by air pressure on the piston; and in both cylinders the exhaust air escapes through passages 34 and 36 to the valve chamber, and from the latter through the exhaust port 28 to the outside air. As the rear piston approaches the division plate the passage 31 is uncovered, passage 35 remaining covered, which allows air pressure to enter the rear end of the valve chamber to drive the valve forward, the exhaust from the forward end of the chamber escaping through passage 25 in the valve head and through exhaust port 28 to the outside air. Both rear piston and valve having reached the forward end of their stroke, air pressure entering at 27 flows through port 36 into passage 34 at the bottom of the division plate thereby causing the rear piston to fly back instantly under no load and the forward piston to move forward as quickly as the rod is reduced to a fluid state and extruded under the pressure exerted on the pistons, the exhaust in both cylinders escaping from the end ports into passage 30 and from the latter through port 33 into the valve chamber and then through exhaust port 29 to the outside air. As the forward piston nears the end of its forward stroke, port 35 is uncovered allowing air pressure to enter the forward end of the valve chamber to drive the valve rearward, the exhaust from the rear end of the valve chamber escaping through passage 26 in the valve head and the exhaust port 29 to the outside air.

It will be obvious from the foregoing description that either one or a plurality of pistons may be used as a fluid actuated motor to propel a rod, or other shaped solid, of uniform cross-section through a guiding tube, or heating chamber, or reduction zone, and that because of the very rapid retractive piston movement the progression of the rod will be substantially continuous whether one or two pistons are used. The extrusion outlet from a guiding tube may be of the same cross-section as the rod, and the latter fed through the outlet without prior heating, and the entire heating and disruption of the rod

into filaments or droplets occur simultaneously and as a result of a blast of heated conveying fluid; or the rod may be gradually heated to a semi-fluid state in a heating chamber, and moved in that condition through an extrusion outlet of the same cross-section as the rod, and the final heating and disruption of the rod into filaments or droplets occur simultaneously with and as a result of a blast of heated conveying fluid; or the rod may be gradually heated to a molten state in a reduction zone, and the fluid end of the rod moved through an extrusion outlet of the same cross-section as the rod, and the disruption of the latter into filaments or droplets result from a blast of heated conveying fluid; but in all three methods the propelling speed of the rod can not be in excess of the speed with which the rod may be disrupted into filaments, and up to that point may be regulated by an adjusting screw for admitting air pressure to the cylinder. However, it is usually more desirable that the extrusion outlet contain one or more openings of smaller cross-section than the rod, and the first disruption result from the propulsion of the molten plastic from a reduction zone into streams through the openings, the movement of the pistons and rod depending on the speed with which the rod may be reduced to a fluid state and forced through openings, which speed can be regulated by the length and thermostatic control of the heating elements and the adjusting screw for the fluid pressure to the cylinders. The reducing of the rod to a molten state within a reduction zone may be wholly due to pressure of the rod against a solid heating surface having extrusion openings therethrough, but it will usually be found preferable to bring the rod to a molten state progressively and use piston pressure to force the near-molten and deformable end of the rod against enclosing walls adjacent to the outlet openings for final heating and extrusion of the molten rod through the openings. The filaments may be extruded and conveyed and deposited in relatively great lengths, but for most purposes are disrupted by the primary conveying fluid into comparatively short lengths, which may be made substantially uniform by a periodic interruption in the blast of the fluid by means of a rotating valve in the fluid feed line or a uniform intermittent pressural contact on the gun trigger that may control a valve in the feed line. It will be noted that the entire propulsion mechanism may be replaced by an upright air-vented container for a molten plastic or a plastic solution, the container having a side flange for insertion into the recessed portion of the gun stock and the guiding tube forming the outlet connection from the center of the flange to the extrusion head, and the liquid being forced through the latter under a differential pressure as in ordinary liquid spray guns.

It will also be evident that solids and fluids of various types may be introduced in either or both of the conveying fluid streams: smooth surface fibres, such as glass, asbestos, rayon, nylon, etc., some of which may be potentially adhesive possessing latent coalescent characteristics and become binder fibres when subjected to heat or/and pressure, but which cannot be felted by ordinary means, may be fed into the streams for commingling with binder fibres in a plastic state, and both binder and non-binder fibres then deposited to form a felt; or the non-binder fibres, and the binder fibres in a plastic state, may be deposited in successive or alternate layers to form a felt,

and in either case the felt compacted by pressure either before or subsequent to complete induration of the binder fibres in the felt. Or, if because of the distance the filaments have to be thrown to form a covering, or for other reasons, they become indurated or lose their adhesive characteristics too soon, a solvent for the filaments, such as acetone for cellulose acetate fibres, may be fed into one of the conveying streams to increase and/or maintain the adhesiveness of the binder fibres for the non-binder fibres introduced in the other of the conveying streams. Likewise, saturated or superheated steam of any desired temperature and moisture content may be introduced into one of the conveying streams for the same reason, as well as for heating purposes.

It will furthermore be evident that a fusible material that cannot be reduced to filaments, may be reduced to droplets by exactly the same method and apparatus used to reduce other fusible materials to filaments; and a fusible fibre-forming material may be reduced to droplets by modifying the conditions required for reducing it to filaments, such as by varying the temperature and viscosity of the fluid material, direction and pressure of the dispersing fluid at the time and point of disruption, etc.; or a fusible fibre-forming material may be reduced to droplets by finely dividing it, and introducing the discrete particles into a conveying stream of suitable temperature to reduce the particles to a fluid state while the latter are in a dispersed condition, and the deposition may be accomplished simultaneously and in mixture with the filaments, or subsequently to the deposition of the filaments.

It will still furthermore be evident that the word "spraying" is equally applicable to the dispersion of various discrete solids, such as filaments, and the dispersion of the very finely divided liquid particles, referred to in the specifications and claims as "droplets"; and it will be understood that the word "rod" is meant to include shaped articles of uniform cross-section, such as ribbons, sheets, and the like.

I claim as my invention:

1. The method of producing filaments of substantial strength from a thermoplastic material comprising: feeding the said material in a solid rod of uniform cross-section into a reducing zone; subjecting the said material to heat and pressure in the said zone to reduce the material to a fluid condition; alternating the said fluid material into a plurality of filaments by pressure of the oncoming solid rod; and stretching and conveying the said filaments by a blast of elastic fluid.

2. The method of producing filaments of substantial strength from a thermoplastic material comprising: feeding the said material in a solid rod of uniform cross-section into a reducing zone; subjecting the said material to heat in the said zone to reduce the material to a fluid condition; attenuating the said fluid material into a plurality of filaments; dispersing and conveying the said filaments by a stream of an elastic fluid; and progressively feeding fresh rod material into the said zone in direct ratio to the rate of reduction of the solid rod material to a fluid condition.

3. The method of producing filaments of substantial strength from a thermoplastic material comprising: feeding the said material in a solid rod of uniform cross-section into a reducing zone; subjecting the said material to heat and pressure in the said zone to reduce the material to a fluid condition; attenuating the said fluid material into a filament by extrusion of the material from

9

the said zone through an orifice under pressure of the oncoming solid rod; disrupting the said filament into a plurality of filaments of irregular lengths by a blast of an elastic fluid; and progressively feeding fresh rod material into the said zone in direct ratio to the rate of extrusion of the fluid material from the zone.

4. The method of producing filaments of substantial strength from a thermoplastic material comprising: feeding the said material in a solid rod of uniform cross-section against the solid surface of a heating element possessing a temperature sufficiently high to reduce to a fluid condition that portion of the rod adjacent to the said surface; attenuating the said fluid material into a plurality of filaments by forcing the material from the said surface through an extrusion outlet by pressure of the oncoming solid rod; and stretching the said filaments by a blast of elastic fluid.

5. In a spinning device, the combination of: a feeding chamber; a receptacle connected to the said chamber; propelling means in the said chamber for progressively feeding a solid material into the said receptacle; heating means in the said receptacle for reducing the said material to a fluid condition; an extrusion outlet from the said receptacle for disrupting the said fluid material into a plurality of filaments as the said solid material is fed out of the receptacle; means for supplying an elastic fluid for stretching and conveying said filaments as they are extruded; and means for introducing a treating agent into the said elastic fluid to render the said filaments adhesive during the said conveyance.

6. In a spinning device, the combination of: a feeding chamber; a receptacle having a heating surface therein; a conduit from the said chamber to the said receptacle; an outlet from the said receptacle; propelling means in the said chamber for feeding a solid material at a uniform speed through the said conduit, and against the said heating surface in the said receptacle, and extruding a melted portion thereof through the said outlet into a plurality of filaments; and means for supplying an elastic fluid to the said filaments and for moving the fluid in a helical path to stretch and convey the filaments as they are extruded.

7. In an apparatus for disintegrating a solid rod of uniform cross-section, the combination of: a feeding chamber; a piston adapted to reciprocate in forward and retractive movements within the said chamber; means within the said piston for gripping the said rod in the forward movement of the piston and releasing the rod in the retractive movement of the piston; a receptacle connected to the said chamber and having an extrusion outlet therefrom; heating means for reducing a portion of the said rod within the said receptacle to a fluid condition; and means for supplying fluid pressure to the said chamber to reciprocate the said piston whereby the said rod is fed from the chamber into the said receptacle as rapidly as the said portion within the receptacle is reduced to a fluid condition and extruded from the receptacle.

8. In an apparatus for disintegrating a solid rod of uniform cross-section, the combination of: a feeding chamber; a pair of pistons adapted to reciprocate in opposing forward and retractive movements within the said chamber; means within the said pistons for gripping the said rod

5 10 15 20 25 30 35 40 45 50 55 60 65 70 75 80 85 90 95

in the forward movements of the pistons and releasing the rod in the retractive movements of the pistons; a receptacle connected to the said chamber and having an extrusion outlet therefrom; heating means for reducing a portion of the said rod within the said receptacle to a fluid condition; and means for supplying fluid pressure to the said chamber to reciprocate the said pistons in opposing directions whereby the said rod is fed continuously from the chamber into the said receptacle and as rapidly as the said portion within the receptacle is reduced to a fluid condition and extruded from the receptacle.

9. The method of producing filaments from a thermoplastic material comprising: progressively feeding the said material into a melting zone; subjecting the said material to heat in the said zone to reduce the material to a fluid condition; disrupting the said fluid material into a plurality of heated filaments; stretching and conveying the said heated filaments by movement of a primary fluid to attenuate the filaments; and quenching and conveying the said attenuated filaments by movement of a secondary fluid to deposit the filaments.

10. The method of producing filaments from a thermoplastic material comprising: progressively feeding the said material into a melting zone; subjecting the said material to heat in the said zone to reduce the material to a fluid condition; disrupting the said fluid material into a plurality of heated filaments; stretching and conveying the said heated filaments by movement of a primary fluid to attenuate the filaments; quenching and conveying the said attenuated filaments by movement of a secondary fluid to deposit the filaments; and introducing a treating agent into the said secondary fluid during the said quenching and conveying to make the said filaments adherent to one another upon deposition.

11. In a spinning device, the combination of: a feeding chamber; a receptacle having a heating surface therein; a conduit from the said chamber to the said receptacle; an outlet from the said receptacle; propelling means in the said chamber for feeding a solid material at a uniform speed through the said conduit, and against the said heating surface in the said receptacle, and extruding a melted portion thereof through the said outlet into a plurality of filaments; and means for supplying an elastic fluid to the said filaments and for moving the fluid in a helical path to stretch and convey and wind the said filaments about one another as they are extruded.
